CLAIM

The ornamental design for a battery powered face brush, substantially as shown and described.

DESCRIPTION

FIG. 1 is a top angular perspective view showing a battery powered face brush according to my new design;

FIG. 2 is a perspective view with a bottom angular view thereof;

FIG. 3 is a right side view thereof;

FIG. 4 is a left side view thereof;

FIG. 5 is a front view thereof;

FIG. 6 is a back view thereof;

FIG. 7 is a top plan view thereof;

FIG. 8 is a bottom plan view thereof; and,

FIG. 9 is a perspective view indicating the battery powered face brush as insertable in a face brush holder shown in dashed lines.

The broken lines in the drawing depict portions of the battery powered face brush that form no part of the claimed design.
